UNITED STATES PATENT OFFICE.

JAY W. POWERS, OF WINNETKA, ASSIGNOR TO THE HYDRO-PNEUMATIC MANUFACTURING COMPANY, OF CHICAGO, ILLINOIS.

FORCE-PUMP.

SPECIFICATION forming part of Letters Patent No. 425,389, dated April 8, 1890.

Application filed December 14, 1888. Serial No. 293,560. (No model.)

To all whom it may concern:

Be it known that I, JAY W. POWERS, a citizen of the United States, residing at Winnetka, in the county of Cook and State of Illinois, have invented new and useful Improvements in Force-Pumps, of which the following is a full, clear, and exact description, reference being had to the accompanying drawings, which form a part of this specification, where-

10 in—

Figure 1 is a side elevation; Fig. 2, a longitudinal section; Fig. 3, an end view of the body or principal part with its heads removed; Fig. 4, a cross-section from *a* to *a*; Fig. 5, a longitudinal section of a modified construction; Fig. 6, another modification, and Fig. 7 still another modified form.

Like letters refer to like parts in the several views.

20 A is an air-chamber; B, the body or principal part; C, the piston, and D the plunger. The air-chamber is not unlike that of any other pump either in construction or operation.

25 The body B is furnished with the heads *b* and *b'*, the suction-pipe *c*, the discharge-pipe *d*, and the parallel longitudinal chambers *e* and *f*. The head *b'* is provided with a stuffing-box *g*, of the usual construction. The 30 suction-pipe *c* is centrally located on the body B—that is to say, midway between its opposite ends—and is provided with the flange *h*, to which connecting-pipes may be attached. The discharge-pipe *d* may be located at any 35 desired position upon the body B, (provided always that it communicates with the chamber *f*,) but preferably opposite the suction-pipe *c*, as shown. The longitudinal chamber *e*, within which the plunger D reciprocates, 40 must be cylindrical and smooth and of uniform diameter. It communicates with the chamber *f* by means of the ducts *i* and *i'*, located at their extreme ends, the two chambers being of equal length, and having their ends 45 covered by the heads *b* and *b'*. The longitudinal chamber *f* has at its central portion, or directly beneath the discharge-pipe *d*, an enlarged portion or recess *j*, within which the ball *k* is placed, which operates as a double 50 check-valve.

The piston C consists of a short cylinder fitting an interior chamber of the plunger D and a rod *C'* extending therefrom outward through the stuffing-box *g* of the head *b'*.

The plunger D is constructed as follows: 55 Upon its outer surface at or near its opposite ends are placed annular packing-rings *l l*, fitting the chamber *e* closely. Between these packing-rings *l l* is an annular groove *m*, which should be about half as long as the chamber *e*, to the end that it shall at all times be in communication with the suction-pipe *c*. It is further provided with an interior longitudinal chamber *n*, into either end of which 60 rings or glands *o o* are secured, thus making the chamber *n* smaller in diameter at its opposite ends, and leaving a cylindrical recess *p* in its center somewhat longer than the piston C designed to reciprocate therein. This recess *p*, which is somewhat longer than 65 the piston C, communicates with the annular groove *m* by means of the ports *q* and *q'*, located near its opposite ends. These ports should be such a distance apart that the piston C when at half-stroke shall just cover 70 both of them, thus providing for a lap when the piston is at full stroke in either direction.

The operation of my pump is as follows: Starting with the plunger D at the inner end 75 of the chamber *e*, (power being applied to the piston-rod *C'*), the piston C first moves outward without imparting motion to the plunger D until it contacts with the gland *o'*, which forms for it a seat. Through this operation the ports *q*, communicating with the 80 inner end of the chamber *e*, are opened, and the ports *q'*, communicating with its outer end, are closed; and, as the piston C continues on its outward stroke, carrying the plunger D along with it, the imprisoned fluid 85 in the outer end of the chamber *e* is forced out through the duct *i'*, the longitudinal chamber *f*, and the discharge-pipe *d*, the ball *k* moving to its seat *r*, which prevents the fluid 90 from flowing into the inner end of the chamber *e*, while at the same time fluid is flowing in through the suction-pipe *c*, the annular groove *m*, and the ports *q* to fill the inner end 95 of the chamber *e*, made vacant by the outward stroke of the plunger D. In the reverse 100

operation the piston C first moves inward without imparting motion to the plunger D until it contacts with the gland o. Through this operation the ports q' , communicating 5 with the outer end of the chamber e, are opened, and the ports q , communicating with its inner end, are closed; and as the piston C continues on its inward stroke, carrying the plunger D along with it, the imprisoned fluid 10 in the inner end of the chamber e is forced out through the duct i, and the longitudinal chamber f, and the discharge-pipe d, the ball k moving to its seat r' , which prevents the fluid from flowing into the outer end of the 15 chamber e, while at the same time fluid is flowing in through the suction-pipe c, the annular groove m, and the ports q' , to fill the outer end of the chamber e, made vacant by the inward stroke of the plunger D.

20 In the modified construction shown in Fig. 5, Sheet 2, I dispense with the longitudinal chamber f as an integral part of the body B, and substitute therefor the detachable elbows s, pipes t, and three-way T u, within which I 25 place the ball k, and to which I attach the discharge-pipe d and air-chamber A. The operation of this modified construction is substantially the same as that of the one shown in Figs. 1, 2, 3, and 4, and needs no repetition.

30 In the modification shown in Fig. 6 I substitute for the ball k a short cylinder v, reciprocating within the recess j' of the longitudinal chamber f.

In the modified form shown in Fig. 7 I 35 place the valve-chamber j^2 above and outside the body B and have it communicate with

the chamber f by means of two ports w and w' , but close the chamber between the ports, thus dividing the chamber f into two chambers or passages, the two outer ends of which 40 communicate with the longitudinal chamber e and the two inner ends with the valve-chamber j^2 . Within this valve-chamber j^2 , I place the short cylinder or valve k², which operates (through its reciprocating motion) to 45 alternately open and close the ports w and w' .

Either and all of these modifications I hold to be mechanical equivalents of the device shown in Figs. 1, 2, 3, and 4, and therefore as belonging to my invention.

What I claim as new, and desire to secure by Letters Patent, is—

In a force-pump, the combination of the cylinder B, substantially as described, with the piston C, recessed within the plunger D, and adapted to move longitudinally a short distance therein without imparting motion to the plunger D, whereby the ports q and q' are alternately opened and closed, and the plunger D, provided with annular packing-rings 60 l l , the annular groove m, the recess p, and the ports q and q' , connecting the groove m and the recess p, the whole being arranged and operated substantially as and for the purposes set forth.

In testimony whereof I affix my signature in the presence of two witnesses.

JAY W. POWERS.
